UNITED STATES PATENT OFFICE.

HENRY B. MORRIS, OF ITHACA, NEW YORK, ASSIGNOR TO THE AUTOPHONE COMPANY, OF SAME PLACE.

MECHANICAL MUSICAL INSTRUMENT.

SPECIFICATION forming part of Letters Patent No. 268,925, dated December 12, 1882.

Application filed February 13, 1882. (No model.)

To all whom it may concern:

Be it known that I, HENRY B. MORRIS, a citizen of the United States, residing at Ithaca, in the county of Tompkins and State of New York, have invented certain new and useful Improvements in Automatic Musical Instruments; and I do hereby declare the following to be a full, clear, and exact description of the invention, such as will enable others skilled in the art to which it appertains to make and use the same.

This invention relates to that class of automatic wind instruments which produce musical sounds through the agency of a perforated music-sheet or valve-sheet.

The object of the invention is to utilize the pneumatic pressure obtained from the reservoir-bellows of the instrument to keep the valve-sheet tightly pressed against the orifices leading to the pipes or reeds; and to this end the invention consists in securing a movable presser-bar in such relation to the reed or pipe apertures, or the ducts leading thereto, by means of flexible connections that it will press the valve-sheet closely against such ducts or apertures when the instrument is in operation, guide-pins being provided to steady the presser-bar in its movements.

In order that my invention may be understood and practiced by those skilled in the art, I will proceed to describe the same in connection with the accompanying drawing, which represents a side elevation, partly in section, of an automatic wind instrument embodying my improvements.

Mounted in the lower part of the frame A of the instrument is the supply-bellows B, the top board, b, of which extends the entire length and width of the frame, and is rigidly secured thereto. The board b is provided near one end with an exit-port, b', leading into an air-passage, C, which conducts the air to the inlet-port d of the reservoir-bellows D. The top board of this reservoir-bellows D is permanently fixed to the top A' of the instrument; but the bottom board is movable vertically, and interposed between this movable bottom and the rigid top b of the bellows B are suitable stout springs D', which tend to force the bottom board of bellows D upward, thus forcing the air from said bellows through the exit-

port d' thereof. The usual valve is interposed between the supply-bellows B and the reservoir-bellows D.

Rigidly supported above the top board, A', of the frame, and extending across the instrument, is a bar, E, provided with vertical holes e, leading to the pipes or reeds F, placed above said bar. I prefer to face the lower rounded side of this bar E with metal.

The valve-sheet G is wound upon and operated by the rollers H H', mounted above the top of the instrument—one in front and one in rear of the pipes or reeds F, as shown—and passes about midway between the rolls beneath the bar E. Between the top A' of the instrument and the bar E, and parallel with said bar, is mounted a presser-bar, I, provided with vertical holes i, arranged to register with the vertical holes e in the bar E. This presser-bar is connected to the top A' of the instrument by means of a strip, I', of leather, rubber, or other suitable flexible material, in such a manner as to admit of a slight vertical movement of said bar; and to steady the bar in its movement I provide guide pins i', which project above the top A' of the instrument and enter sockets in the under side of the presser-bar I. When the instrument is at rest the presser-bar falls toward the top A', thus leaving a space between said bar and the bar E for the insertion of the valve-sheet; but upon the development of a pneumatic pressure by working the bellows B the presser-bar will rise and press the valve-sheet close against the bottom of bar E, thereby preventing any improper escape of air. When the bellows has ceased to operate the diminution of pneumatic pressure permits the presser-bar to fall to its lowest position for the insertion of another valve-sheet.

The shaft of roll H is provided at one end with a crank, h, for operating it, and fixed to its other end is a crank, h', for operating the bellows B through the agency of a pitman, h².

As the operation of this class of instruments in producing harmonies through the agency of a valve-sheet is well understood, I do not deem it necessary to describe the same herein.

Having thus described my invention, what I claim is—

1. The combination, substantially as before

set forth, of a wind-chest of an automatic wind instrument, and a perforated presser-bar flexibly connected therewith and operated by pneumatic pressure from the bellows of said instrument.

2. The combination, with a wind-chest of a musical instrument, substantially as before set forth, of the presser-bar, the guide-pins, and the flexible connecting-strip.

10 3. The combination, with a wind-chest of a

musical instrument, substantially as before set forth, of the presser-bar, the guide-pins, the flexible connecting-strip, the bar E, and the valve-sheet.

In testimony whereof I affix my signature in presence of two witnesses.

HENRY B. MORRIS.
